WORK HOLDER MECHANISM FOR
MACHINE TOOLSBernard P. Schiltz, Cleveland, Ohio, assignor to
The Foote-Burt Company, Cleveland, Ohio, a
corporation of Ohio

Application September 27, 1945, Serial No. 618,922

6 Claims. (Cl. 90—59)

1

The present invention pertains to work holder mechanisms for machine tools and more particularly to such mechanisms in which the work is automatically clamped and unclamped in the course of movement of the holder through the machine.

One object of the invention is to provide a mechanism of the class indicated in which safety means is provided for automatically arresting motion of the holder in the event of failure of the clamp actuating mechanism.

More particularly, it is an object to provide such a mechanism employing a hammer cam for operating successive ones of a series of work clamping devices, together with means for automatically arresting further operation of the machine in the event of a failure of the hammer cam to effect proper operation of one of the devices.

Another object is to provide means for preventing breakage of the hammer cam or associated elements in a mechanism of the class indicated when the motion of the work holder is reversed, as for example upon an inadvertent reversal incident to plugging an electric drive motor for the work holder.

Further objects and advantages of the invention will become apparent as the following description proceeds, taken in connection with the accompanying drawings, in which:

Figure 1 is a side elevation of a continuous-type broaching machine embodying the present invention, a portion of the housing and bed structure being broken away to expose the interiorly located parts.

Fig. 2 is an enlarged fragmentary plan view of the entrance or right-hand portion of the machine shown in Fig. 1.

Fig. 3 is an enlarged detail view partially in section along the line 3—3 in Fig. 4 showing the hammer cam and associated parts included in the machine of Fig. 1.

Fig. 4 is an enlarged transverse sectional view taken substantially along the line 4—4 in Fig. 1.

Fig. 5 is a schematic wiring diagram of the electric controls of the machine.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

2

Referring more particularly to the drawings, the invention has been illustrated therein as embodied in a continuous-type broaching machine. Since the present invention has primarily to do with the work holder mechanism incorporated in the machine, simply a brief outline of the machine structure as a whole will suffice. As shown, the machine is provided with a hollow base 10 supported by legs 11 (Fig. 1). Sectional broaches 12 are carried by a bridge 14 mounted on the bed intermediate its ends and constitute in effect the top wall of a tunnel through which successive workpieces are passed. Sheet metal covers or housings 15 may be provided to enclose the end portions of the machine.

Workpieces, such as indicated at W (Fig. 1), are received in a series of work holders designated generally as 16 and are carried by the latter beneath the broaches 12 so that the latter shear the top surfaces of the workpieces, machining the same in the manner customary in broaching. The work holders 16 are mounted between a pair of endless chains 17 trained over sprockets 18 carried on shafts 19 journaled in opposite ends of the bed 10. One of the shafts 19 is driven by a suitable electric drive motor (not shown in Fig. 1 but indicated at 20 in the wiring diagram of Fig. 5).

In the normal operation of the machine, the work holders 16 are advanced continuously through their endless path. The operator places the workpieces W in successive ones of the holders at the right-hand or entrance end of the machine as viewed in Fig. 1. As the holders approach the tunnel in which the broaches 12 are located, suitable clamping devices incorporated in each of the holders are automatically actuated into clamped position. After the holders emerge from the tunnel, their clamping devices are automatically unclamped and the finished workpiece may be removed.

Each work holder 16 includes a clamping device comprised of a fixed jaw 21 and a movable jaw 22. Each fixed jaw 21 is rigid with a base plate 23 having pins 24 (Figs. 2 and 4) protruding laterally therefrom and on which are journaled appropriate ones of the links 25 which make up the endless chains 17. The movable jaws 22 are fashioned in the form of blocks received in longitudinally extending guideways 26 on the upstanding forward portions 23a of the base plates 23. Guides 10a (Fig. 4) carried by suitable transverse webbing 10b in the bed 10 slidably receive the base plates 23 in the course of their travel beneath the broaches.

Each movable jaw 22 is equipped with a co-acting actuator bar 27 (Fig. 2) which is movable endwise to cam the jaw into and out of clamping position. Such actuator bars 27 are slideable endwise in alined transverse holes 28 in the upstanding portions 23^a of the base and also pass through generally centrally located transverse apertures 29 in the movable jaws 22. The leading and trailing edges of the bars 27 are relieved to form sloping surfaces 30 arranged to coact with complementally shaped protrusions 31 on the inner side walls of the apertures 29 in the movable jaws. The slope of the surfaces 30 is such that, upon an endwise movement of one of the actuator bars in a downward direction as viewed in Fig. 2, the cooperating jaw 22 is cammed or wedged into clamping position against the work-piece W, whereas upon movement of the actuator bar in the opposite direction the movable jaw is withdrawn into unclamped position.

A hammer cam 32 (Figs. 2, 3 and 4) is employed for driving successive ones of the actuator bars 27 endwise as they are presented to it and in a direction to effect clamping of the work. In the present instance, the hammer cam 32 is fashioned in the form of an elongated arm pivoted on a pin 33 alongside the path of travel of the work holders to swing toward and from the latter. A spring 34 (Fig. 3) yieldably urges the hammer cam into position to intercept successive ones of the actuator bars 27. This spring is shown as a helical compression spring located in a tubular housing 35 having an adjusting plug 36 threaded in its outer end and a hollow plunger 37 slidably received in the inner end. The nose of this plunger bears against the outer side of a dog 39 carried on the end portion of the hammer cam and thus urges the latter to swing toward the work holders with a force which may be varied by threading the adjusting plug 36 in or out. A stop 32^b limits the swing of the hammer cam 32 inward toward the work holders.

The outer end portion of the hammer cam 32 is transversely apertured, as indicated at 38 in Fig. 3, to receive the dog 39 mentioned above. Such dog is pivoted within the aperture on a pin 40, the dog being of L-shape. The forward side wall of the aperture 38 forms an abutment or stop 41 against which the dog is urged by the spring pressed plunger 37. The dimensions of the aperture 38 are such as to afford clearance for the dog 39 to swing counterclockwise (as viewed in Fig. 3) away from the abutment 41 and when so swung the nose of the dog is withdrawn within the aperture 38. The element 39 thus constitutes a one-way dog. Normally, the spring pressed plunger 37 holds the dog 39 in the out-thrust position shown in Fig. 3, a location in which the protruding nose of the dog constitutes a drop-off on the hammer cam and over which the ends of the bars 27 ride.

The ends of the actuator bars 27 are sloped rearwardly, as indicated at 27^a, complementally to the slope of the leading edge 32^a of the hammer cam when it occupies its unstressed position indicated in broken lines in Fig. 3. It will be observed that the protruding nose portion of the dog 39 is also relieved or sloped as indicated at 39^a to present a surface alined with the edge 32^a of the hammer cam when the dog is in its fully projected position.

As each successive actuator bar 27 comes into contact with the hammer cam 32, its end portion 27^a slides progressively along the edge 32^a of the hammer cam, thrusting the latter outward from

the broken line position of Fig. 3 and compressing the spring 34 to thereby cock or load the hammer cam mechanism. During such outward swing of the hammer cam it moves out beyond the full line position shown in Fig. 3 and at the same time the bar 27 is thrust inward but not sufficiently to fully complete clamping of the work. As the bar 27 continues to move forward, the projecting nose of the dog 39 rides over the end of the bar and finally drops off of the same into the position shown in full lines in Fig. 3. As an incident to such drop, the compressed spring 34 drives the hammer cam 32 against the end of the actuator bar, causing a sharp blow to be delivered to the latter. The actuator bar 27 is thus driven endwise still further and completes the wedging of the cooperating movable clamp jaw 22 into clamping position.

In the event that one of the actuator bars 27 should stick or for any reason offer more than normal resistance to movement, it would, without else, simply shoulder the hammer cam 32 aside a greater distance than normal and continue on without clamping the work. In accordance with one aspect of the present invention, provision is made for automatically arresting further motion of the work holder 16 in the event of such improper operation. For that purpose, a plunger 42 (Fig. 3) is arranged to slide endwise within a housing 42^a at the outer side of the hammer cam 32. A compression spring 42^b urges the plunger 42 toward the hammer cam, the plunger being located so that it remains clear of the hammer cam during normal movement of the latter. In the event the actuator bar 27 fails to shift, the hammer cam is, however, thrust outward a greater than normal distance and thus contacts the plunger 42, shoving it outward. Such movement of the plunger 42 causes its outer end portion to push downward the actuating button 43 of a switch located within a housing 44, the switch being designated as 45 in the wiring diagram of Fig. 5. A resultant opening of the switch serves to stop the drive motor 20, as will hereinafter appear in further detail in connection with the description of the control circuits.

As a further safety measure to insure proper location of the workpieces W in the holders 16 prior to the presentation of the workpieces to the broaches 12, provision is also made for automatically stopping the holder drive motor 20 whenever one of the workpieces protrudes too far upward out of the holder. For that purpose a flap or shield 46 (Figs. 1 and 4) is mounted on a pivot shaft 47 at the entrance end of the tunnel. A tension spring 48 connected to an eccentric lug 49 on an arm 50 fixed to the end of the shaft 47 normally holds the shield 46 yieldably in vertical position, the arm being pressed against a switch operating button 51. In the event that a workpiece protrudes too far above the holder it strikes the shield 46, swinging the latter inward of the tunnel, so that a cam surface 50^a on the arm 50 (see also Fig. 2) depresses the actuating button 51 of a switch housed within the casing 52 and designated as 53 in the wiring diagram of Fig. 5.

At the exit end of the tunnel (left end as viewed in Fig. 1) is located a stationary cam 54 (see also Fig. 4) which abuts against successive ones of the actuator bars 27 and restores them to their initial or unclamped position. The workpieces are thus freed from successive holders as they emerge from the broach. The cam 54 is, as shown, located on the side of the machine op-

posite the hammer cam 32 and may be in the form of a simple fixed block presenting a face inclined in the direction of bar travel and complementary to the adjacent inclined ends 27^b (see Fig. 2) on the bars.

Referring now to the control circuit shown in Fig. 5, it will be noted that a pushbutton start switch 55 is provided as well as a pair of pushbutton switches 56, 57. These switches may be located at any convenient point on the machine with the stop switches located, for example, at opposite ends so that the machine can be readily stopped wherever the operator may be. Current is supplied for the motor 20 from three phase supply lines L₁, L₂ and L₃.

To start the machine in operation, the operator closes the "start" switch 55 momentarily. This completes an energizing circuit for the actuating winding F of a "forward" contactor by connecting the same across lines L₁, L₂ through a conductor 58 which is connected to the latter line. When the forward contactor is thus picked up, it closes its main contacts F₁ which connect the motor 20 across the supply lines for rotation in a forward direction, and at the same time opens its auxiliary contacts F₂ and closes its auxiliary contacts F₃. Opening of the contacts F₂ disables the plugging circuit to which further reference is made below, whereas F₃ are holding contacts in shunt with the "start" switch 55 so that the forward contactor remains energized even though the "start" switch is closed only momentarily.

With the motor 20 running in its forward direction, the work holders 16 are advanced in succession beneath the broaches 12, moving beneath the latter in a leftward direction as viewed in Fig. 1. As each successive work holder moves around to the top of the righthand sprocket 18 the machine operator drops a fresh blank or workpiece into it. Thereafter the hammer cam 32 engages the work holder's actuator bar 27 and thrusts it inward to close the clamping jaw 22, finally driving the bar home with a sharp hammer blow, all as previously detailed. As the work holders emerge from the tunnel after completion of the broaching, the opening cam 54 shoves the actuator bars 27 back to open each work holder's clamping device. An operator stationed at such end of the machine can then lift out the unclamped finished workpiece or they can be permitted to fall into a receptacle located beneath the lefthand sprocket 18 if desired.

In the event that the hammer cam 32 fails to move one of the actuating bars 27 fully into clamping position, the hammer cam is thrust outward against the switch actuating plunger 40 (Fig. 3) as previously described, thereby opening the safety switch 45. Similarly, if one of the workpieces is not pushed down fully into the work holder, it strikes the shield 46 and swings the latter so that the other safety switch 53 is opened. Opening of either of the safety switches 45 or 53 or the opening of either of the stop switches 56 or 57, causes the drive motor 20 to be plugged to an immediate stop. It will be noted that all four of the switches 45, 53, 56 and 57 are connected in series so that the opening of any one of them has the same effect on the circuit.

As to the stopping operation, it will be noted that opening of any one of the series of switches 45, 53, 56 or 57 drops out the "forward" contactor so that its auxiliary contacts F₂ reclose. This completes an energizing circuit between

lines L₂ and L₃ for the actuating winding F of a "reverse" contactor, such circuit being completed through a plugging switch PS. The plugging switch may be of conventional form, including a pair of contacts which are normally open and moved to closed position by a mechanical connection with the motor and remaining closed until the motor is substantially at rest. Energization of the reversing contactor causes it to close its main contacts R₁ to apply reverse voltage to the motor, thereby quickly plugging it to a stop.

Normally the plugging switch PS is set to remain open as the motor comes to rest and thereby drops out the reversing contactor so that the motor is left deenergized in stopped position. Because of maladjustment of the plugging switch or for other reasons, it sometimes happens in such a set-up, however, that the motor 20 will actually reverse at least for a few revolutions. In such case the last one of the actuator bars 27 to pass the hammer cam may be moved back into contact with the latter and if the drop-off shoulder on the hammer cam were formed by a rigid projection, breakage would ensue. It is to prevent such breakage that the drop-off shoulder is, in the present instance, defined by the dog 39 previously described. This being a one-way dog, if the end of an actuator bar is reversed into contact with it, the bar will simply swing the dog counterclockwise (as viewed in Fig. 3) so that the bar 27 can pass freely and without damage.

I claim as my invention:

1. In a machine tool, the combination of a work holder mounted for movement in a confined path and having a clamping device thereon, power actuated means for moving said holder, actuating means for said clamping device including a pair of members arranged with one on said holder and the other located alongside the path of such holder in position to intercept the first as the holder moves along its path, both of said members being shiftable transversely of said path, the shift of said one member serving to actuate said device, means for yieldably retaining said other member in a position in which said one member rides over it as it passes, said yieldable means being strong enough to normally overcome the resistance to shift of said one member and thereby effect a shift of the latter to actuate said clamping device, and safety means for stopping said power actuated means in response to a retraction motion of said other member in excess of a predetermined amount, whereby further travel of said holder is automatically arrested in the event said one member fails to shift for actuation of said clamping device and instead shoulders said other member aside as it passes the same.

2. In a machine tool, the combination of a work holder mounted for movement in a confined path and having a clamping device thereon, power actuated means for moving said holder, actuating means for said clamping device including a movable member carried by said holder and a coacting cam movably mounted alongside the path of such holder in position to intercept said movable member as the holder moves along its path, means for yieldably retaining said cam in a position in which said movable member rides over it as the member passes, said yieldable means being strong enough to overcome the normal resistance to shift of said movable member and thereby effect a shift of the latter to actuate said clamping device, and safety means for stopping said power actuated means in response to a retraction motion of said

cam in excess of a predetermined amount, whereby further travel of said holder is automatically arrested in the event said movable member fails to shift for actuation of said clamping device and instead shoulders said cam aside as it passes the same.

3. In a machine tool, the combination of a work holder mounted for movement in a confined path and having a clamping device thereon, power actuated means for moving said holder, a hammer cam movably mounted alongside the path of said holder, an actuating member for said clamping device movably mounted on said holder and presenting means for loading and firing said hammer cam as the holder passes the same, said member being arranged for movement under the impact of said hammer cam upon firing of the latter, a safety switch for stopping said power actuated means, and a movable operating member for said safety switch mounted adjacent said hammer cam, said operating member being adapted to trip said safety switch in response to a loading motion of said hammer cam in excess of a predetermined amount.

4. In a machine tool, the combination of a work holder mounted for movement in a confined path and having a clamping device thereon, reversible electric drive motor for moving said holder, a hammer cam pivotally mounted alongside the path of said holder and yieldingly urged toward the same, an actuating member for said clamping device movably mounted on said holder and projecting outward toward said hammer cam, a one-way dog mounted on said hammer cam and defining an abrupt drop-off shoulder presented to said actuating member as the latter underrides said hammer cam, said dog being mounted to swing freely clear of said member in the event of a reversal of the latter by said holder, and safety means for plugging said motor in response to movement of said hammer cam outward away from said holder in excess of a predetermined amount.

5. In a machine tool, the combination of a work holder having clamping jaws and an actuator bar slidable endwise for moving such jaws into and out of clamping position, means including a reversible electric drive motor for moving said holder through a confined path in which said actuator bar lies transverse to the direction of movement, a hammer cam mounted alongside said path for movement toward and from the adjacent end of said actuator bar as the latter

passes, a spring yieldably urging said cam into a position in which it intercepts the end of said bar as said holder advances, a dog pivoted on the active end of said hammer cam and spring urged against a fixed stop on the latter which locates said dog in position to project outward toward the path of said bar, said bar and cam having co-acting surfaces thereon for camming said hammer cam back against the urging of said first mentioned spring and thereafter abruptly releasing the same for application of a hammer blow to said bar to drive the latter endwise as said bar rides off of said dog, and means for plugging said drive motor in response to camming of said hammer cam outward beyond a predetermined fixed distance, the pivotal mounting of said dog permitting said holder to reverse its motion without breakage of said hammer cam and bar.

6. In a machine tool, the combination of a plurality of work holders each having a clamping mechanism, power actuated means for moving said holders in succession along a fixed path, a hammer cam mounted for movement toward and away from said path for actuating said clamping mechanisms one after another as the respective work holders pass such hammer cam, a one-way dog pivoted on said hammer cam for movement between an out-thrust position and a withdrawn position, said dog being adapted when in the out-thrust position to intercept a coacting portion of each successive clamping mechanism, an abutment on said hammer cam for defining the out-thrust position of said dog, and yieldable means effective during normal movement of said holders for maintaining said dog against said abutment and in said out-thrust position, said yieldable means being adapted upon reverse movement of said holders to permit free pivoting of said dog away from said abutment and toward said withdrawn position.
